(57) **CLAIM**

The ornamental design for a visual load break switch blade status indicator, as shown and described.

DESCRIPTION

FIG. 1 is a top view of a visual load break switch blade status indicator showing our new design;

FIG. 2 is a front view thereof;

FIG. 3 is a right view thereof;

FIG. 4 is a left view thereof;

FIG. 5 is a rear view thereof;

FIG. 6 is a front isometric view thereof; and,

FIG. 7 is a rear isometric view thereof.

Dashed (broken) lines represent structure or features that form no part of the claimed design.
